(57) **CLAIM**

The ornamental design for a watch body, as shown and described.

DESCRIPTION

This application incorporates by reference U.S. application Ser. No. 29/534,057 and U.S. application Ser. No. 29/534,052. All the material from U.S. application Ser. No. 29/534,057 and U.S. application Ser. No. 29/534,052 that is essential to the claimed design is included in this Application. It is understood that any material in U.S. application Ser. No. 29/534,057 and U.S. application Ser. No. 29/534,052 that is not present in this Application forms no part of the claimed design.

FIG. 1 is a top perspective view showing a watch body according to our new design from a first end;

FIG. 2 is a bottom perspective view showing the watch body from the first end;

FIG. 3 is an end view of the first end of the watch body;

FIG. 4 is a top perspective view showing the watch body from a second, opposite end;

FIG. 5 is a bottom perspective view showing the watch body from the second end;

FIG. 6 is an end view of the second end of the watch body;

FIG. 7 is a plan view of a top of the watch body;

FIG. 8 is a side view showing a right side of the watch body;

FIG. 9 is a plan view showing a back of the watch body; and,

FIG. 10 is a side view of a left side of the watch body.

The broken line showing of a band represents environment and forms no part of the claimed design. The remainder of the broken lines represent portions of the watch body that form no part of the claimed design.

1 Claim, 3 Drawing Sheets
